Peter Lawson, Lowell, Mass. Letters Patent No 203.
dated Oct 24th 1848. (Assigned to Lowell Manufacturing Co)

The Schedule referred to in these Letters Patent and making part of the same

To all to whom these Presents shall come: Be it known that I, Peter Lawson, of Lowell, in the County of Middle sex, and State of Massachusetts, have invented a new design to be woven into or upon carpets and for other purposes and that the following is a full, clear and exact description of the principle, or character which distinguishes it from all other things before known, and of the usual manner of making, modifying, and using the same, reference being had to the accompanying drawing in which the design is fully set forth.

The design numbered 753 consists of a meandering vine, or foliated wreath a winding between shields b, to be hereafter described; said wreath is interspersed with flowers c of various colors upon a ruby ground. The shields are enclosed between two pillars d with urn-shaped ornaments e above their capitals and supporting an arch f, the key of which is pendant and has foliated ornaments thereon; the shield is white spotted with ruby, and upon the shield are oak leaves and acorns h; below the base of the columns the border of the shield terminates in a pendant i and volutes.

It will be observed in this design that several colors are interspersed in the figure without any appearance of stripes, and green leaves together with blue, red, and yellow flowers are displayed, and commingled with an admixture of leaves formed of brown and yellow without the introduction of the ruby ground, except for the shades, whilst the shields are pure white with the simple introduction of a sufficiency of the ground to tie the fabric properly: these features are entirely new, and as such are believed to be patentable; they were made at great cost of time, labor, and skill; the difficulties of which are apparent to all who are acquainted with designing for woven fabrics.

Therefore what I claim as my invention, and for which I desire to obtain letters patent is first the combination of colors herein described so as to form on a ruby ground white shields said white shields having figures of yellow and brown or orange "shot about" drawn thereon - and the columns or scrolls forming the outlines of said shields being of yellow & brown or orange "shot about" shaded with ruby & brown or orange "shot about" and the said yellow or brown or orange "shot about" used also as figuring on the ruby ground - in combination with blue heads "shaded roses and green leaves introduced as above exemplified for weaving into carpets. Secondly, I claim the above described design as delineated in the accompanying drawing.
